CLAIM

The ornamental designs for a slider device for resealable closure, as shown and described.

DESCRIPTION

FIG. 1 is a top perspective view of a slider device in accordance with the invention.

FIG. 2 is a bottom perspective view of the slider device.

FIG. 3 is a right end elevational view of the slider device.

FIG. 4 is a left end elevational view of the slider device.

FIG. 5 is a top plan view of the slider device.

FIG. 6 is a bottom plan view of the slider device.

FIG. 7 is a front side elevational view of the slider device; and,

FIG. 8 is a rear side elevational view of the slider device.
